UNITED STATES PATENT OFFICE.

WILLIAM VOSS, OF WILMINGTON, DELAWARE, ASSIGNOR TO AMERICAN CAR AND FOUNDRY COMPANY, OF ST. LOUIS, MISSOURI, A CORPORATION OF NEW JERSEY.

CAR-ROOF.

1,052,774.

Specification of Letters Patent.

Patented Feb. 11, 1913.

Original application filed August 27, 1910, Serial No. 579,323. Divided and this application filed September 21, 1911. Serial No. 650,661.

To all whom it may concern:

Be it known that I, WILLIAM Voss, residing at Wilmington, Newcastle county, Delaware, and being a citizen of the United States, have invented certain new and useful Improvements in Car-Roofs, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is an elevational view of the carline employed indicating the relative positions of the principal members thereof and their relation to the side walls of a car. Fig. 2 is a detail cross sectional view through approximately one-half of a car roof, illustrating the carline and the manner of connecting adjacent structural parts of the car, a portion of said figure being detached so as to facilitate the enlargement of the scale of the drawing. Fig. 3 is a horizontal sectional view, partly in top plan, said section being taken substantially on the plane of line 3—3 of Fig. 2, and Fig. 4 is a detail vertical sectional view taken substantially on the plane of line 4—4 of Fig. 2.

The object of the invention is to provide a roof structure of simple and substantial design, suitable for use in passenger car construction such as is illustrated in my pending application Serial No. 579,323 of which this application is a division.

The invention comprises a carline structure formed of three principal elements: a channel member as 1, outlining the exterior cross sectional contour of the car roof; and a pair of angle sections as 2—2, outlining the interior cross sectional contour of the car roof; each of said members being preferably commercially rolled sections.

The channel member 1 comprises a central, or upper deck section 3, and two end or lower deck sections as 4—4. The flanges of the channel are turned downwardly and the inner end portions of each of the lower deck sections 4—4, at the point of the inner

edge of the lower decks, are bent into up-standing portions as 5—5 which extend upwardly to and support the upper deck section 3. The upper ends of the webs of the portions 5 are extended between the flanges of the upper deck section 3 at points spaced somewhat from the adjacent ends of said section 3 so as to leave overhanging portions for ornamentation and for attachment of the usual screen plates as 6. The flanges of the upper ends of the portions 5 are cut away to admit the pendant flanges of the section 3, and angle brackets as 7, connect the web of the section 3 with the webs of the portions 5.

The outer end of each of the sections 4 is bent downwardly to give the customary exterior roof contour and the lower end of each of said sections is rested squarely upon the upper surface of the angle section side plate 8 of the car wall structure, and is fixed thereto by suitable angle brackets as 9.

The angle sections 2—2 are parallelly disposed upon opposite sides of the channel member and are continuous from side to side of the car, being fixed at their opposite ends, by suitable splice plates as 10, to longitudinal T rails as 11 carried upon the inner surfaces of side posts 12 of the car walls.

Between the inner edges of the lower decks, the angles 2 are arched and the central portions thereof are fixed to the flanges of the upper deck channel section 3. The lower deck portions of the angles 2 conform approximately to the contour of the portions 4 of the channel member 1 for part of the length of said portions 4. The outer end portions of said angles are however, bent downwardly somewhat more abruptly than are the corresponding portions of the channel sections so as to conform to the interior cross sectional contour of the roof, and are fixed to the T rails as before described.

Each of the angles 2 is arranged with one of its flanges upstanding and with the other flange projecting outwardly from the lower edge of said first flange, and those portions of the upstanding flanges which lap the pendant flanges of the channel sections are connected by rivets to said channel sections.

An upper deck roof plate 13 covers the channel section 3 and each longitudinal edge

thereof is formed into a pendant flange as 14 which overhangs the adjacent end of the channel section and laps the upper longitudinal edge of the adjacent screen plate 6.

5 The features of construction of the opposite sides of the roof being identical, one side only is illustrated in detail and a description of one side will suffice for both, as follows: The upper edge of the ventilator window plate 15 is extended between the flange 14 and the end of the channel section 3. A longitudinally extending filler plate 16 is also secured between the flange 14 and the end of the channel 3, said plate being bent longitudinally below the lower edge of the flange 14, into an offset portion forming a water table as at 17. The upper edge of the screen plate 6 is disposed intermediate the window plate 15 and filler plate 16 and all of said plates, and the flange 14, are secured to the end of the channel section 3 by through rivets engaging suitable angle brackets 18 fixed to the flanges of said channel section. The window plate 15 is formed 25 with a horizontally disposed portion as 19, extending longitudinally near its upper edge, so that the main body portion of said plate is set inwardly from the screen plate 6 as is customary. The lower edge portion of the window plate is bent to conform to the shape of the lower deck as at 20 and is lapped over the inner longitudinal edge of the lower deck roof plate 21, being fixed to said roof plate preferably by rivets as at 22. 30 Window frames as 23 are secured in suitable openings, such as are usually formed at intervals throughout the length of the window plate.

If desired, instead of being formed of a single plate with openings for the window frames as described, the window plate 15 may comprise an independent upper section extending longitudinally above the window frames, a lower section extending longitudinally beneath the window frames, and with 45 separate plates between the windows.

Adjacent the windows the members of the carline are incased by finishing plates 24, 25 and 26, the plate 24 being fixed to the inner faces of the outwardly extending flanges of angles 2-2 and bridging the space between said angles, and the plates 25 and 26 being Z shaped in horizontal cross section and having their outer flanges fixed to the window plate 15 and their inner flanges lapping the inner face of the plate 24. (See Fig. 3.)

Pressed finishing beads as 27 are secured over the lapping portions of the plates 24, 25 and 26 by bolts which fix said plates to the flanges of the angles 2. The plates 25 and 26 are preferably side portions of interior window hoods, and the upper wall 28 of each of said hoods has its outer edge flanged downwardly and fixed to the inner 65 surface of the adjacent portion of the win-

dow plate 15 by some of the rivets which secure the window frame 23 to said window plate. The inner edge of the plates 25 and 26 are shaped to conform to the curvature of the adjacent portions of the angle sections and the inner edge of the wall 28 is flanged and fixed to a lower longitudinal edge portion of the lining plate 24, where said plate extends uninterruptedly along the middle part of the car. The juncture 70 between the wall 28 and the plate 24 is covered by a longitudinally extending finishing bead 29 against which the upper ends of the beads 27 are adapted to abut for producing a desirable interior finish. This construction forms an arched buttress within the roof portion of the car permitting of numerous variations of ceiling finish.

The lower deck roof plate 21 rests upon the upper surface of the web of the adjacent channel section 4 and the lower edge of said plate depends beyond the end of said channel and laps the outer face of the side plates 8. The fascia plate or letter board 30 has its upper longitudinal edge portion extending between the outer face of the side plate 8 and the inner face of the pendant portion of the roof plate 21. Interposed between the outer face of the fascia plate and roof plate is a filler 31 which has its lower longitudinal edge offset so as to provide a water table similar to the water table 17 at the edge of the upper deck. The fascia plate, the filler, and the lower edge of the roof plate are secured to the side plate 8 by suitable through rivets as at 32.

A lining plate 33 is fixed to the inner flanges of the lower deck portions of the angles 2 and an ornamental finishing molding 34 extends longitudinally of the car along the inner edge of the lower deck section for covering the juncture between the plates 33 and 24 and for forming an appropriate window sill for the ventilator windows.

What I claim is:—

1. A car roof comprising a compound carline, one member connecting the wall plates and conforming to the outer contour of the car roof, and an inner supporting arch member having a curve at the middle sharper than that of the outer member and connected to the middle of the outer member to support the same.

2. A car roof comprising a compound carline, one member connecting the wall plates and having a monitor roof outline and supporting the roof plates and an inner member having a compound curve extending from wall to wall and connected to the outer member at the inner edges of the lower deck and at the middle of the upper deck portions of the outer member.

3. In a car, the combination with side walls, of a carline comprising a plurality

- of principal members, one of said members being shaped to conform to the exterior contour of the car roof, and the other of said members being shaped to conform to the interior contour of the car roof and comprising a trefoil arch supporting the roof contour at three points, both of said members extending across the car from wall to wall and the roof contour members being spaced from the supporting arched member between supporting points. 5
4. In a car, the combination with side posts and side plates, carline members connecting the side plates and forming the contour of the car roof, arch members attached to and supporting the roof contour members at the inner edges of the lower deck, and the center of the upper deck portions and forming an arch contour for the car ceiling, sheathing for said arch contour members forming arched buttresses at intervals along the car roof, and ventilator windows in the car roof intermediate the arched buttresses of the ceiling of the car. 10
5. In a car, the combination with side walls, of a carline comprising a plurality of principal members extending across the car from wall to wall, one of said members being shaped to conform to the exterior contour of the car roof, another of said members being fixed to said first member through a part of its length and having portions spaced from said first member adapted to conform to the interior contour of the car roof, and comprising a trefoil arch supporting the roof contour at three points and roof plates fixed to one of said members. 15
6. In a car, the combination with side posts and side plates, of carline members connecting the side plates and forming the contour of the car roof and provided with proper sheathing, arched members supporting the car roof contour members and forming an arch contour for the car ceiling and provided with a suitable sheathing forming casings intermittently throughout the length of the car and extending into the roof portion of the car and ventilator windows in the roof sheathing between said casings. 20
7. In a car, a carline comprising a plurality of principal members, one of said members comprising an upper deck section and lower deck sections, said lower deck sections being bent at their inner edges into upstanding portions connected to said upper deck section, and others of said members being fixed to said lower deck sections at opposite sides thereof, and being arched into contact with said upper deck section between the inner edges of said lower deck sections and being fixed to upper deck section, roof plates fixed to one of said members, and lining plates fixed to said other members. 25
8. In a car, a carline comprising a plurality of flanged members, one of said members comprising an upper deck section and lower deck sections, others of said members being continuous from end to end of the carline and comprising a trefoil arch supporting the roof contour at three points and being fixed to flanges of each of the sections of the first member, and roof plates fixed to one of said members. 30
9. In a car, a carline comprising a plurality of principal members, one of said members comprising an upper deck section and lower deck sections, said lower deck sections being bent at their inner edges into upstanding portions connected to said upper deck section at points spaced from the ends of said upper deck section, and window plates fixed to said upstanding portions having portions extending beyond and fixed to the ends of said upper deck section. 35
10. In a car, a carline comprising a plurality of principal members, one of said members comprising an upper deck section and lower deck sections, said lower deck sections being bent at their inner edges into upstanding portions connected to said upper deck section at points spaced from the ends of said upper deck section, window plates fixed to said upstanding portions extending beyond and fixed to the ends of said upper deck section, and a roof plate fixed to said upper deck section and lapping a portion of said window plates. 40
11. In a car, a carline comprising an upper deck section and a lower deck section, said lower deck section being bent into an upstanding portion fixed to said upper deck section, a window plate fixed to said upstanding portion, said window plate having an offset part lapping the end of said upper deck section, a roof plate fixed to said upper deck section having a pendent flange lapping said offset part, and a water table extending between said roof plate and window plate. 45
12. In a car, a carline comprising an upper deck section and a lower deck section, said lower deck section being bent into an upstanding portion fixed to said upper deck section, a window plate fixed to said upstanding portion, said window plate having an offset part lapping the end of said upper deck section, a roof plate fixed to said upper deck section having a pendent flange lapping said offset portion, a screen plate extending between said flange and offset portion, a water table extending between said flange and offset portion, and means connecting said flange, water table, screen plate, and offset portion to the end of the upper deck section. 50
13. In a car, the combination with side posts, and a side plate connecting said posts, of carlines sustained thereby, a roof plate fixed to the carlines and depending outside

- of the side plate, a fascia plate having a portion interposed between the side plate and the depending portion of the roof plate, a filler strip disposed between the fascia plate and the depending portion of the roof plate, means securing the depending portion of the roof plate, the filler strip, fascia plate, and side plate together, the filler strip extending below the depending portion of the roof plate and being bent to form a water table.
14. In a car, a carline comprising a plurality of principal members, one of said members comprising an upper deck section and lower deck sections, said lower deck sections being bent at their inner edges into upstanding portions connected to said upper deck section, and others of said members being fixed to said lower deck sections at opposite sides thereof and being arched across the car, and casings inclosing said arched members and extending upon opposite sides of said upstanding portions.
15. In a car, a carline comprising a plurality of principal members, one of said members comprising an upper deck section and lower deck sections, said lower deck sections being bent at their inner edges into upstanding portions connected to said upper deck section, and others of said members being fixed to said lower deck section at opposite sides thereof and being arched across the car, window plates fixed to said upstanding portions, and casings inclosing said arched members and extending upon opposite sides of said upstanding portions and being fixed to said window plates.
16. In a car, a carline comprising a trefoil arch supporting member extending from wall to wall of the car and provided with flanges forming the contour of the inner car wall roof sections, intermediate partially arched members conforming to the roof of the car, both of said members conforming for a portion of their arch shape and roof plates fixed to the roof supporting members.
17. In a car, a carline comprising a trefoil arch supporting member extending from wall to wall of the car and provided with flanges forming the contour of the inner car wall, roof sections, intermediate sections partially arched and partially spaced from the supporting members and conforming to the outer roof section, and roof plates attached to the roof supporting members.
18. In a car, a carline comprising a trefoil arch supporting member forming the inner contour of the inner roof section, a trefoil drop arch supported by and seated at three points to the inner trefoil arch and forming the outer roof section and suitable sheathing therefor.
19. In a car, a carline comprising an inverted channel section conforming in contour to a typical monitor roof frame, a trefoil arch section attached to and supporting said roof frame at the apex of each arch of the trefoil arch, and covering plates for the roof section.
20. In a car, the combination with side posts of carline members connecting said side posts, one member being formed with lower deck portions bent at the inner edge of the lower deck and upstanding therefrom and upper deck portions, the other member forming a compound arch across the car and supporting the deck carrying portions and roof plates fixed to the said deck portions.
21. In a car, a compound carline comprising inner and outer contour framing members in form of compound arches fixed together at a plurality of points and spaced apart at the base of the carline and intermediate the center of the span thereof.
22. In a car, a compound carline comprising inner and outer contour framing members in form of compound arches spaced apart at the base of the carline, fixed together at the center of the span thereof and spaced apart intermediate the base of the carline and the center of the span thereof.
23. In a car, a carline comprising a plurality of principal members, the web of one of said members comprising an upper deck member and a lower deck member, another of said members being fixed to the lower deck member and forming a trefoil arch for supporting the lower deck member and the upper deck member and being fixed to the upper deck member, and plates fixed to the said deck members.
24. In a car, the combination with side plates of a carline comprising a plurality of principal members extending across the car and connecting said side plates, one of said members being disposed to form the exterior contour of the car roof and the other of said members being disposed to form the interior contour of said car roof and forming a trefoil supporting arch for the car roof contour, the said roof contour member being spaced from the supporting member between supporting points and roof plates fixed to the roof member and lining plates fixed to the lower arches of the supporting member.
25. In a car, a carline comprising a pair of continuous spaced members in form of compound arches and interposed sectional members forming deck sides and roof, the spaced members forming a support for the interposed deck side and roof members and spaced away therefrom beyond said support and roof plates fixed to the said deck side and roof members.
26. In a car roof, compound carlines comprising a support for said car roof, one member thereof forming the contour of the lower

and upper deck portions and the deck side portions, and another member arched to support the lower deck portions at their inner edges and upper deck portions intermediate of its span, ventilators in the deck side portions and sheathed arched members intermediate the ventilators forming buttresses supporting the upper deck.

27. A car roof comprising a compound carline in form of a compound curve, one member connecting the side wall plates and conforming to the contour of the car roof and spaced inner supporting members in form of a compound curve fixed to the roof contour members at the intersecting points of the curves and spaced therefrom intermediate such fixed points.

28. A car roof comprising a compound carline in form of a compound curve, one member thereof connecting the outer wall plates of the car and forming a trefoil arch extending from wall to wall of the car, a second member spaced from the first and conforming to the inner wall line of the car and forming an inner trefoil arch and fixed to the said outer arch at the apex of the curve of each arch.

In witness whereof I have hereunto set my hand in the presence of two witnesses.

WILLIAM VOSS.
